LIQUID FUEL BURNING APPARATUS

Milton A. Powers and Noel H. Sutterfield, Detroit, Mich., assignors to The Timken-Detroit Axle Company, Detroit, Mich., a corporation of Ohio

Application November 27, 1942, Serial No. 467,136

15 Claims. (Cl. 158—4)

1

The present invention relates to liquid fuel burning apparatus, and is particularly concerned with oil burners of the wall flame type, in which combustion is limited to an annular zone located adjacent the combustion chamber wall.

This invention is an improvement upon the wall flame oil burner disclosed in Powers Patent No. 2,039,607. Burners made in accordance with the latter patent employ curved and straight segments. In square or rectangular furnaces it was necessary to employ combinations of straight and curved segments. In circular chambers only curved sections are used. In some installations it is necessary to employ segments having two different degrees of curvature, to build up a flame rim that will follow the contour of the furnace wall sufficiently closely to give the desired efficient burner operation. This made it necessary for the dealer to stock a number of each kind of segment, and to also employ skilled workmen to make burner installations.

It is the major object of this invention to provide a wall flame oil burner having all of the advantages of the burner disclosed in the aforementioned Powers patent, but embodying a flame rim made up of a plurality of comparatively short segments of identical shape and size, which are so designed, and are connected together in such manner that they may be assembled to form a continuous flame rim, closely following the contour of the wall of the combustion chamber in which they are installed, irrespective of whether the chamber is of square, round, oblong or obtund cross-section, and yet which is substantially oil and air tight, thereby making it possible to stock segments of a single design and size, and also facilitating assembly even by comparatively unskilled workmen.

A further important object is to provide a flame rim igniter segment made of plain sheet steel and having a heat resistant coating for protecting its exposed surfaces from the heat of combustion and also embodying a heat resistant electrically conductive section located in sparking relationship to an electrode, for effecting efficient ignition when the burner is started.

Another object is to provide a flame rim segment for a wall flame burner which is made of plain sheet metal and has a heat resistant coating for protecting its surfaces against direct exposure to the combustion gases and is so designed that it will not undergo harmful distortion, even when heated to extremely high temperatures.

Further objects are to provide a segmental flame rim assembly which is adjustable as to

2

length, to enable it to be exactly fitted to the combustion chamber, and in which the joints between the segments are so related to the oil projecting head as to preclude projection of oil through the joints during burner operation; to provide novel grill and segment assemblies which may be so installed as to provide concentric flame rim and grill rings; to provide improved means for securing the flame rim in place on the hearth and which will insure proper spacing thereof from the combustion chamber wall; and to provide other subordinate wall flame oil burner improvements and refinements.

Further objects will become apparent as the specification proceeds in conjunction with the annexed drawings.

In the drawings:

Figure 1 is a fragmental, vertical sectional view through an oil burner embodying the invention;

Figure 2 is a top plan view of a pair of adjacent segments of Figure 1, showing the manner in which they are telescoped together;

Figure 3 is a front elevation of the segment assembly of Figure 2, and illustrates the pair of supports for one of the grills in place on the impingement wall;

Figure 4 is a fragmental sectional view taken on the line 4—4 of Figure 3, looking in the direction of the arrows;

Figure 5 is an enlarged, fragmental sectional view of the upper edge of one of the segments shown in Figure 1;

Figure 6 is a view similar to Figure 2, but illustrates a pair of segments of modified form, and also illustrates the parts in the position they assume adjacent a straight walled portion of the combustion chamber;

Figure 7 is a front elevational view of the segment assembly shown in Figure 6;

Figure 8 is a right-hand end elevational view of the structure shown in Figure 7;

Figure 9 is a view similar to Figure 8, but illustrates a modified form of igniter assembly forming part of the invention;

Figure 10 is a top plan view of the construction shown in Figure 9, the hearth material being removed and the flame rim being shown in section to more clearly illustrate the assembly;

Figure 11 is a side elevational view of a modified form of flame rim segment of the invention; and

Figure 12 is a front elevational view of the segment shown in Figure 11.

With continued reference to the drawings, in which like reference characters have been em-

ployed to designate similar parts throughout the several views thereof, the invention has been illustrated as installed in a boiler installation embodying a boiler B having a heated water section 11 supported on a base section 12. The boiler shown is of circular cross-section, but the invention is applicable to boilers of other shapes, as will be hereinafter pointed out.

Secured to the boiler base section by studs 13 and nuts 14 is a metal hearth plate 15 carrying a hearth 16 of suitable refractory material, which may be molded into finished form and assembled at the factory with the novel flame rim structure of the present invention, or if desired, assembly of the flame rim and molding of the hearth may be carried out on the job. Secured in a central opening 17 in the hearth is a distributor assembly D, comprising a motor driven shaft 18 rigidly carrying a fan top 19 provided with a plurality of blades 21. Shaft 18 also rotatably supports a distributor cup (not shown) which centrifugally delivers oil to a plurality of oil flinger tubes 22, which rotate with the fan and cup.

The head operates in a well known manner to project a stream of unatomized oil droplets along the general trajectory indicated by the arrows 22a toward the flame rim F, and also delivers a blast of air below the oil trajectory along a separate path designated by the arrows 23, for deflection by the low flame rim wall into intersection with the oil atomizing and vaporizing on the impingement wall of the flame rim, in the manner to be hereinafter pointed out.

If desired chrome alloy sheet metal may be used to construct the flame rim and grills, but we have discovered that it is possible to successfully utilize thin, low cost, non-heat resistant steel flame rims in wall flame oil burners by providing the rim with a protective vitreous coating sufficiently thin to render the rim assembly thermally conductive to promptly respond to combustion conditions adjacent the combustion zone, and thick enough to protect the metal against oxidization or carburization.

By making a flame rim of a plurality of identical comparatively short segments and joining them together in overlapping relationship, a set of segments may be assembled in overlapping relationship on the hearth to form a substantially continuous wall in combustion chambers of round, square, elliptical or oblong shape with the flame rim closely following the contour of the wall, and a thoroughly practical construction provided.

Referring to Figures 1 to 5, inclusive, the flame rim F of this form of the invention is made up of a plurality of segments 25 seating directly upon the hearth and anchored thereto. Each segment is of channel shape having a low, air deflecting wall 26 located in the path of air projection, a higher oil impingement wall 27 located in the path of the oil droplets thrown by the distributor head, and a flat base portion 28, which seats upon the hearth. Preferably welded to the rear face of the oil impingement wall of each segment is a securing element 29, provided with an opening 31, and is pointed to facilitate pushing it into the plastic hearth. As seen in Figures 1 and 3, each member 29 is embedded in the hearth while the hearth material is still plastic. The hearth material flows into openings 31 and provides a direct mechanical interlock with the hearth when the material has hardened, thereby firmly anchoring the segments in place.

Referring to Figures 2 and 3, one end of each segment is provided with an enlarged socket por-

tion S, which receives the end of the neighboring segment, thereby forming an overlapping or telescoping joint. The socket is formed by pressing out or embossing portions 32, 33 and 34 in the air deflecting wall 26; the oil impingement wall 27; and base portion 28 of the segment, respectively. As seen in Figure 2, the socket is pressed out of the base portion along a line 35, which is inclined with respect to the segment axis so that the segments may be assembled either in the angular relationship illustrated in Figure 2, or in a straight line relationship along the straight portions of boilers of square or rectangular cross-section, sufficient play or lost motion being provided in the joints to permit free articulation during assembly, and yet fitting sufficiently tight to form substantially oil and air tight joints. In either event a joint is formed which is substantially oil and air tight, and the invention accordingly provides a segmental flame rim having continuity substantially throughout its length, and, because of the nature of the overlapped joint between the segments, and the fact that the segments are comparatively short, the segments may be made of identical size and shape and a plurality of them installed in any type boiler, irrespective of whether it is of square, rectangular, round or elliptical cross-section, and assembled on the hearth so as to provide a flame rim closely following the contour of the boiler wall.

Mounted upon each pair of neighboring segments is a grill G of the character shown in Cole Patent No. 2,104,691, granted January 4, 1938. Each grill is provided at each end thereof with a support 37 having a pair of notches 38. The grills are adapted to be supported upon the flame rim, with the upper edge of the impingement wall of each segment received in a notch of each support, as illustrated in Figure 1, and if desired the grills may be inverted and supported in the other pair of notches when it is desired to vary the mixing action of the grills, as disclosed in the aforementioned Cole patent.

As indicated by the illustration of the grill supports in Figure 3, the relationship between the grill and segment lengths is such that the grills are slightly shorter than the combined overlapped length of two segments, with the result that any even number of segments may be installed in a boiler and a complete set of grills, providing substantially a continuous grill ring, installed in place on the flame rim.

In the embodiment of the invention chosen for illustration the segments and segment legs are preferably made of twenty gauge vitreous enameled steel; "Armco" iron sheets; or S. A. E. 1010 or its equivalent plain sheet steel specially pickled for enameling. The segments are each two inches long plus the overlap. The grills are preferably made with the legs located three and one-half inches apart and made of twenty gauge material, for additional strength and stiffness.

Since it is impractical to bend any of the parts after they have been enameled, the parts are formed into final shape before they are enameled, as will now be described.

The grills and segments are thoroughly coated by dipping or spraying with a silica frit or other suitable heat-resistant vitreous enamel coating, denoted in Figure 5 by the reference character 39, particular attention being paid to coat the sharp edges of all parts, and all surfaces subjected to high temperatures. The parts are then subjected to a high temperature baking process, the baking temperature being in excess of 1600

degrees Fahrenheit, so as to materially exceed the temperatures to which the parts will be subjected during normal operation, thereby insuring long life of the enamel coating and thorough protection of the coated surfaces.

During installation the hearth is built up of refractory ceramic material to the required thickness, and while it is still plastic the segments are mounted thereon, assembled in overlapping relationship and spaced the proper distance from wall 11, and securing elements 29 are forced down into the hearth material. In conversion installations having small or poorly accessible combustion chambers, the segments may be supplied assembled in overlapped relationship secured together by a band of adhesive or "Scotch" tape along the inside of wall 27. The complete ring is thus inserted into the chamber, and since the adhesive tape permits articulation at each joint, the flame rim may be accurately placed on the hearth to follow the contour of wall 11, irrespective of whether it is of round, square, oblong or elliptical configuration. The tape may be left in place, as it will burn away upon starting of the burner. Since the segments are comparatively short it is possible to employ identical shape and size segments in all installations to build up a rim having straight portions or curved portions of comparatively short radius and yet provide a continuous flame rim structure, relatively free from air and oil leaks. Also, because of the nature of the overlapped joints, it is possible to increase or decrease, by minor amounts, the length of the flame rim on the job to exactly adapt it to the combustion chamber size. The overlapped joints also permit free expansion and contraction of the segments in response to heating and cooling.

After the rim has been installed on the hearth as just described, the hearth material is preferably permitted to set, and then a set of grills is applied to the flame rim. One of the grills is illustrated in place on the flame rim in Figure 1, with notches 38 seating on the impingement wall. Notches 38 are formed to final shape before enameling takes place, with sufficient lost motion to avoid the necessity of bending the parts during assembly to properly fit the rim. As indicated in Figure 3, each grill has a length slightly less than the combined length of two overlapped segments, with the result that when a set of grills is in place on the segments they are disposed closely together so as to form a substantially complete grill ring, paralleling or concentric with the ring of flame rim segments.

The improved burner of the invention operates in substantially the same manner and produces results comparable to those set forth in the aforementioned Powers and Cole patents.

Ignition is effected in well known manner, as for instance by means of a pair of electrodes located adjacent the front face of impingement wall 27, or if desired a single electrode may be located in spark-forming relationship to the front face of a single chrome alloy steel unenameled segment, the latter functioning as a second electrode. The unatomized oil droplets projected along the trajectory 22a are both atomized and vaporized by impact with heated impingement wall 27, and the air flowing along the trajectory 23 is deflected upwardly by wall 26 into intersection with the oil atomizing and vaporizing on wall 27 adjacent the top of the flame rim. Combustion takes place above and outwardly of the flame rim, part of the combustion gases eddying behind wall

27 and transferring heat by contact, directly to wall 11 and to the rear face of wall 27, while a part of the gases are driven upwardly through the apertures of grills G and burn closely adjacent the upper surfaces of the grills, providing a flame having a blue base and yellow tips, directed against wall 11 in efficient heat transferring relationship therewith.

Impingement wall 27 is accordingly heated to a high oil vaporizing temperature by the combustion gases eddying behind it, and also by reason of heat radiating directly downwardly from grills G. The temperature of the segments however is kept below temperatures that would melt the enamel or otherwise injure the segments, by the rapid re-transfer of excess heat by radiation, part of it directly from wall 27 to boiler wall 11.

In Figures 6 and 7 there is illustrated a modified form of segment 25a of substantially the same shape as that just described, having a low air deflecting wall 28a and an impingement wall 27a joined by a base portion 28a, but a modified joint is employed between the segments, and additional spacing members are associated with the segments.

In this form of the invention walls 26a and 27a at one end of each segment extend beyond base portion 28a, and are disposed in overlapping engagement with walls 26a and 27a of the adjacent segments, as shown in Figures 6 and 7. The base portions of the neighboring segments meet at a butt joint 44 when they are disposed in the straight line relationship shown in solid lines. When the segments are disposed in angular relationship, as illustrated in dotted lines in Figure 6, there is a triangular opening between the adjacent base sections 28a, but since the segments rest directly upon the hearth, and the space is filled with plastic hearth material, a good joint is nevertheless achieved.

In this form of the invention a modified securing and supporting means is also preferably used. Securing elements 29a are formed in a metal plate or strip 42, secured, as by welding, to the rear face of each segment. Also bent upwardly and rearwardly from each plate 42 is a spacer-leg 43 which bears against wall 11 and assures proper uniform spacing of each segment from the wall during installation, as well as increased hearth bearing support.

As seen in Figures 6 and 7, wall 27a extends further beyond base portion 28a than wall 26a, so that when the segments are disposed in the angular relationship illustrated in dotted lines, a substantially oil and air tight seal between the segments may nevertheless be maintained.

This form of the segment and its grills are enameled and installed on the hearth in the same manner as the one previously described, and is the preferred form because it possesses the additional advantages that spacer-legs 43 definitely insure proper spacing from the wall, and the segment moreover is made of a flat piece of material, obviating the additional costly embossing or socket-forming operations required by the segments of Figures 1 to 5, inclusive, rendering it much cheaper and simpler to produce. Also, these segments lie flat upon the hearth, thus more easily providing an air tight joint.

In both forms of the invention the flame rims are assembled in such manner that the joints 44 and 44a between impingement walls 27 and 27a, respectively, all face in the same direction, and fan 19 is designed to rotate in such direction that the oil droplets discharged from tubes 22 are

thrown in such direction as to avoid driving oil into the overlapped joints.

Referring to Figures 2 and 6, counterclockwise head rotation projects the oil droplets substantially tangentially with respect to the head periphery along outwardly directed paths, one of which is indicated by the arrow 45 in Figure 2. As seen by arrow 45, this direction of head rotation tends to drive the oil past each joint, thereby avoiding driving oil into the joints. This insures against leakage of oil behind the rim during initial operation of the burner.

From the foregoing detailed disclosure of the invention it is apparent that the invention provides a rotary wall flame oil burner providing comparatively short segments of identical size and novel form which may be installed in combustion chambers of round, square, oblong or elliptical shape to build up a flame rim closely following the contour of the boiler wall, and at the same time the assembly provides sufficient freedom of relative longitudinal movement in the joints to allow the length of the flame rim to be slightly increased or decreased during assembly, to exactly fit it to the size of the combustion chamber in which the flame rim is installed.

In Figures 9 and 10 we have shown a modified form of igniter segment which makes it unnecessary to employ one or more special chrome alloy non-enamelled segments to effect efficient ignition.

In this form of the invention hearth 16 is supported on hearth plate 15 as in Figure 1, and preferably two special igniter segments 25b, of the same general character, and enameled as the segments 25a previously described, but each embodying an electrically conductive mass, are substantially diametrically spaced around the flame rim. Welded to the bottom of each igniter segment are a pair of metal strips 51 and 52, whose outer ends cooperate with the boiler wall to space the segment the proper distance therefrom, in the same manner as members 43 of Figures 7 and 8. Strip 51 also has a downturned inner end 29b which is anchored in the hearth.

Located in upright wall 27b, in the area of oil impingement, is an opening 53, and welded to the rear face of the impingement wall, by means of flanges 54 and 55, and aligned with the opening, is a sheet metal cup or pocket-forming member 56, which, as seen in Figure 9, is open at the top and is filled with a mass of electrically conductive material 57. The latter is preferably formed by mixing granular carborundum and a binder and water, to form a plastic mass which, after it has been molded into the pocket, hardens to a solid mass, presenting a face conforming substantially to the face of the impingement wall. If desired, an insulating material may be incorporated in the binder to increase the resistance thereof and cause it to heat up when a current is passed through it. The material is molded into the pocket after it has been enameled and baked, and after the parts, that will now be described, have been secured to the assembly.

Strip 52 is provided with a downturned inner end 59, which is welded to an electrode positioning ring 61 and has a high tension terminal 62 at its lower end. Member 59 passes downwardly through aligned openings in the hearth and hearth plate, and supported on a plate 63, seating on the hearth plate, by means of welded ears 64 and 65, is a split clamp ring 66, whose ends are secured together by a screw 67. The clamp ring is secured to member 59 by a nut and screw assembly 68, which is vertically adjustable there-

on, to compensate for variations in hearth thickness.

Clamped in ring 66 is an insulated electrode assembly 69 having a terminal 71 at its lower end and a curved electrode 72 disposed in sparking or arc-forming relationship to mass 57. The igniters may be energized in well known manner to ignite the impinging oil upon starting the burner, and are preferably connected to a step-up transformer having a relatively high milliamperage output, for producing hot flaming arcs at the impingement wall. Assembly of the parts is preferably carried out as follows.

After all the parts have been welded to segment 25b, including pocket 56, they are all coated with enamel, except the inside surfaces 74 of the pocket, the inside of ring 61, (so that it may be designed to have a snug fit with the igniter assembly) and the portion of member 59 below the level of the ring, and baked to produce a heat resistant coating. Mass 57 may then be molded in place. Plates 63 are then molded in the hearth with the igniter assemblies thereon, and nut and screw assemblies 68 applied. Final adjustment of electrode 72 may be carried out after the hearth has hardened, by loosening screw 67 and rocking the assembly about the vertical axis to establish the proper spark gap.

This assembly accordingly makes it possible to employ ordinary sheet steel for the flame rim igniter segments and associated parts, as all the surfaces exposed to the flame are protected by a heat-resistant coating, and the insides of pockets 56 are protected by masses 57, and an efficient electrical path at each igniter is established through member 59; segment walls 28b and 27b; the inner surfaces 74 of pocket 56; mass 57; the spark gap; electrode 72 and terminal 71.

In Figures 11 and 12 there is disclosed a modified form of segment 25c, of the same general shape as the one shown in Figures 7 and 8, but embodying stiffening or reinforcing means, which prevents the impingement wall from undergoing harmful distortion, even when heated to extremely high temperatures, and also makes it feasible to employ somewhat lighter gauge material than in the previously described forms of the invention.

The reinforcing means comprises a preferably continuous bead or corrugation pressed out of the impingement wall 27c, and having vertical portions 75 and 76 joined by a horizontal portion 77. As seen in Figures 11 and 12, the bead is pressed out so that it projects on the front face of the impingement wall and is offset so that it will not interfere with obtaining an oil-tight joint when the sections are overlapped, portion 76 being spaced inwardly from the right-hand edge of the segment (Figure 11) so that the adjacent segment may lie flush against wall 27c, as indicated in dotted lines, irrespective of whether the parts are assembled in rectilinear or angular relationship.

This form of the invention also illustrates an alternate manner of interfitting the segments. As seen in Figure 12, the projecting wall portions 26c and 27c are located at the left-hand rather than the right-hand side of the segment, as shown in Figures 7 and 8, but the parts are overlapped and function in the same way, and are designed for the same direction of head rotation in both forms of the invention.

The invention may be embodied in other specific forms without departing from the spirit or essential characteristics thereof. The present

embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a liquid fuel burning apparatus, a combustion chamber closed at its bottom by a hearth and having a wall extending around the periphery of the hearth; a flame ring structure mounted on said hearth with all portions thereof substantially uniformly spaced from said wall, said structure being made up of a plurality of structurally independent, straight segments angularly adjustable relative to each other in the plane of the ring and having their neighboring ends disposed in overlapping contacting relationship in all relative positions of adjacent segments to provide substantially oil-tight flexible joints, said joints affording sufficient relative angular displacement of adjacent segments to enable the flame ring structure to accurately follow the contour of the wall of said combustion chamber irrespective of whether the latter is of curved or straight contour.

2. In a wall flame oil burner having a combustion chamber closed at its bottom by a hearth, a flame ring structure made up of a plurality of thin-walled metal structurally independent segments of channel shape section, each having an upright oil impingement wall; an upright air deflecting wall; and a base portion seated upon said hearth, said segments being assembled in end-to-end relationship for relative angular adjustment in the plane of the ring and having the neighboring ends of said walls and base portions disposed in overlapping, substantially oil tight engagement, and means individual to each segment for directly anchoring the same to said hearth.

3. The apparatus defined in claim 2, wherein one end of each segment is provided with an enlarged socket formation of sufficient size to telescopically receive the wall and base portions of the neighboring segment end.

4. In a wall flame oil burner having a combustion chamber closed at its bottom by a hearth, a flame ring structure made up of a plurality of thin segments of channel shape section, each segment having an upright oil impingement wall; an upright air deflecting wall; and a substantially flat base portion adapted to seat upon said hearth; said segments being assembled in end-to-end relationship around the hearth, with the impingement and air deflecting wall portions of each segment extending beyond the base portion at one end of each segment and overlapping the corresponding wall portions of its neighboring segment to provide telescoping, substantially oil and air tight joints between the segments.

5. The apparatus defined in claim 4, wherein the lower edges of the extended portions of said impingement and air deflecting walls are disposed substantially flush with the hearth.

6. The apparatus defined in claim 4, wherein the extended portions of said oil impingement and air deflecting walls are sufficiently long to permit said segments to be so assembled on said hearth as to define a curve of relatively short radius and yet maintain substantially air and

oil tight overlapping relationship with said neighboring walls.

7. The apparatus defined in claim 4, wherein the extended portion of said oil impingement wall is longer than the extended portion of said deflecting wall.

8. In a wall flame oil burner having a combustion chamber closed at its bottom by a hearth and a peripheral wall extending around the hearth, a plurality of relatively short coupled individual combustion ring segments mounted in end-to-end relationship around the hearth in spaced relationship to said wall, each segment having a downwardly directed element secured to said hearth and an outwardly directed member bearing against said wall, to establish and maintain the proper spacing of said segments from said wall.

9. In a wall flame oil burner having a combustion chamber closed at its bottom by a hearth, a plurality of overlapping segments mounted on said hearth in spaced relationship to the combustion chamber wall and providing an upright oil impingement wall; and a plurality of grills having means mounting them on said impingement wall, said segments each being sufficiently short to permit said impingement wall to closely follow the contour of the combustion chamber wall, said grills each being of a length slightly less than the combined overlapped length of two segments, whereby a set of any even number of segments will provide for installation of a series of grills affording a substantially continuous grill ring, and said grill mounting means comprising a pair of legs on each grill adapted to seat upon two adjacent segments.

10. A combustion ring segment comprising a short and longitudinally continuous channel-shaped thin metal member having one end materially enlarged for substantially loose telescopic coupling with the smaller end of an adjacent like segment.

11. In a wall flame oil burner having a combustion chamber closed at its bottom by a hearth, a flame ring structure made of a plurality of thin metal segments of channel shape section, each having an upright oil impingement wall, an upright air deflecting wall and a base portion adapted to seat upon said hearth, said segments being assembled in end-to-end relationship and having the neighboring ends of the walls and base portions disposed in overlapping substantially oil tight engagement, and a downwardly extending element on each segment adapted to be anchored in said hearth.

12. A substantially fluid-tight wall flame ring for fuel oil burners, comprising a plurality of structurally independent linear units of rectangular channel form in cross-section arranged in successive order to form a closed ring, with the confronting ends of the corresponding channel walls of adjacent units in substantially oil sealing contact with each other in the relative angular adjustment of said units in the plane of the ring from an aligned relation of the channels, to provide a flame ring of a desired general contour having substantially continuous channel walls.

13. The wall flame ring as defined in claim 12, wherein the individual ring units are each provided with means for anchoring the same to a combustion chamber hearth.

14. A combustion ring segment comprising a short thin metal member of substantially rectangular channel shape in cross-section having a

11

low front upright air impingement wall, a higher upright rear air impingement wall and a base wall extending between the lower ends of said impingement walls, and at least one of said front and rear walls having an outwardly displaced end portion providing a materially enlarged socket for relatively loose reception of the smaller end of an adjacent like segment.

15. In a wall flame burner having a combustion chamber provided with a hearth, a plurality of short longitudinally continuous thin metal individual combustion ring segments of channel shape in section arranged to provide a substan-

5

10

12

tially continuous combustion ring on said hearth, each segment having a low front air impingement wall, a higher rear air impingement wall and a base wall adapted to be seated on said hearth, and said segments each being formed with a materially enlarged socketed end for receiving in relatively loose overlapped engagement the smaller end of the adjacent segment, said loose engagement permitting arrangement of adjacent segments in required angular disposition to suit the contour of said combustion chamber.
